UNITED STATES PATENT OFFICE

166,616

URINAL HOLDER

Eleanor Grace Mally, Colorado Springs, Colo.

Application March 27, 1951, Serial No. 14,639

Term of patent 14 years

(Cl. D83—1)

To all whom it may concern:

Be it known that I, Eleanor Grace Mally, citizen of the United States, residing at Colorado Springs, in the county of El Paso, and State of Colorado, have invented a new, original, and ornamental Design for Urinal Holder, of which the following is a specification; reference being had to the accompanying drawing, forming part thereof.

In the drawing:

I claim:

The ornamental design for a urinal holder, substantially as shown.

ELEANOR GRACE MALLY.
